UNITED STATES PATENT OFFICE.

CHARLES FRANCIS JENKINS, OF WASHINGTON, DISTRICT OF COLUMBIA.

STARTING DEVICE FOR GAS-ENGINES.

1,003,750.

Specification of Letters Patent. Patented Sept. 19, 1911.

Application filed July 25, 1910. Serial No. 573,821.

To all whom it may concern:

Be it known that I, CHARLES FRANCIS JENKINS, a citizen of the United States, residing at Washington, in the District of Columbia, have invented certain new and useful Improvements in Starting Devices for Gas-Engines, of which the following is a specification.

This invention relates to that class of devices known as gas-engine starters, and its main object is the production of a simple mechanism of reliable efficiency especially adapted to pleasure vehicles.

In the accompanying drawings, Figure 1 is a front view of the device as located on the rear cylinder of a gasolene engine as they are usually situated in an automobile; Fig. 2 is a side view of the cylinder and attached devices; Fig. 3 a view showing the location of small cocks, one on each cylinder, for admitting the starting mixture to the several cylinders, and Fig. 4 a detail of the valve gear.

In the figures, 1 is the rear cylinder of a four-cylinder automobile, a check-valve 2 located on the side of, and communicating with the inside of the cylinder; 3 a lever-valve on the check-valve extension; 4 a relatively large pipe, filled with very small tubes to prevent back-firing in case of accidental disarrangement of the parts; 5 a T into which the lower end of this pipe fits; 6 a small cylinder, the lower end of which is in communication with one branch of the 35 T, the cylinder having a piston working therein, the stem of which is attached to the lever of the lever-cock 3; 7 is a cross one side of which communicates with the lower end of the cylinder 6, another side with the 40 gage 8, another side with a safety-valve 9, and the fourth side with a reservoir 10; 11 is a spring on the lever-cock to turn it to open position under proper conditions; 12 a spring located on the same cock lever to 45 insure quick opening and closing; 13 is a small lever-cock on each cylinder, the levers of all of which are actuated by the rod 14 the inner end of which is located within easy reach of the driver; each of these small 50 cocks is connected by the pipe 15 to the pipe 16 which latter is in communication with the reservoir 10.

17 is the usual spark-plug in the top of the cylinder employed to explode the 55 charge; from this plug a wire 18 leads to the insulated metal blade 19 on the disk

20 located on the stem of the lever-cock 3. This metal blade is so formed and located that when the lever-cock 3 is in the open or dotted position the blade short-circuits the 40 plug 17 by grounding the wire 18 on a metal part of the motor. The wire 21 communicates with the spark-producing mechanism of the regular motor equipment.

The operation of the device is as follows: 65 Assuming the tank 10 contains a full charge of explosive gas under pressure, the small lever-cocks 13 are opened by pushing in on the rod 14 as shown in Fig. 3. This allows gas under pressure to flow into each cylinder. Two of them will be filled with it, and in two of them, as most motors are made, the gas is wasted, though in this invention the simplicity of the arrangement is considered to more than offset the small waste involved. 70 Releasing the rod 14 the spring 12 returns the valves 13 to the closed position, leaving one or more of the cylinders charged with a combustible gas, which is exploded by touching a button, with which latter practically 75 all automobiles are now fitted. This, of course, starts the rotation of the engine, which automatically explodes the charge in the second cylinder, although it has been found that the single impulse of the first 80 explosion is ample for causing the motor to take up its regular cycle.

When the supply of gas in the reservoir has dropped to a predetermined amount the spring 11 overcomes the upward thrust of 90 the piston plus the tension of the spring 12 and the lever-cock 3 is opened, and the spark-plug is short-circuited. The charge drawn into the cylinder, by the rotation of the motor, instead of being exploded as it 95 reaches the top, is forced out through the open cock 3 and ultimately into the reservoir 10. This cycle is repeated at every stroke of the piston until the pressure in the reservoir has reached a certain predetermined point when the pressure of the gas 100 under the piston in the small cylinder 6 pushes the lever up and closes the cock 3. This also, of course, opens the short-circuit of wire 18 and the cylinder immediately 105 takes up its power cycle with the other three cylinders.

This change from power to pump function, and back again, is, obviously, automatic, and in actual practice appears to be 110 imperceptible under the ordinary conditions of automobile use. The apparatus is small

and neat, although, for sake of clearness, has been shown rather large in the drawings. It can be fitted to any car without the necessity of securing a timing of the parts with the rotation of the motor. It has also been found that under certain conditions and arrangements of the parts the motor begins to turn under the impulse of the gas alone and that it then explodes the charge automatically.

10. What I claim, therefore, is—

1. In an internal combustion engine, the combination with a series of explosion cylinders and igniting devices for the same, of a non-explosion cylinder and a plunger therein, means for temporarily rendering the ignition device for one of the explosion cylinders inoperative, thereby converting the cylinder and its piston into a force pump, a conduit leading from the last named cylinder to the non-explosion cylinder to actuate its plunger, and means whereby said plunger when thus actuated may restore the inoperative ignition device to operating condition.
2. In an internal combustion engine, the combination of a plurality of power cylinders, one of which, temporarily, acts only as a pump drawing an explosive gas from the carburetor common to all of the cylinders and compressing it into a reservoir through a valve arranged to automatically close when the pressure in the reservoir reaches a predetermined point.
3. In an internal combustion engine, the combination of a plurality of power cylinders, one of which, temporarily, acts only as a pump drawing an explosive gas from the carburetor common to all of the cylinders and compressing it into a reservoir through a valve arranged to automatically close only when the pressure in the reservoir reaches a

predetermined point, and manually controlled means for distributing this mixture to the several cylinders.

4. In an internal combustion engine, the combination of a plurality of power cylinders, one of which, temporarily, acts only as a pump drawing an explosive gas from the carburetor common to all the cylinders and compressing it into a reservoir through a valve arranged to automatically close when the pressure in the reservoir reaches a predetermined point and to automatically open when the pressure falls to a certain other point.

5. In an internal combustion engine, the combination of a plurality of power cylinders, one of which, temporarily, acts only as a pump drawing an explosive mixture from the carburetor common to all the cylinders and compressing it into a reservoir through a valve arranged to automatically open and close, and means for short-circuiting the spark-plug on the pumping cylinder.

6. In an internal combustion engine, the combination of a plurality of power cylinders, one of which, temporarily, acts only as a pump drawing an explosive mixture from the carburetor common to all the cylinders and compressing it into a reservoir through a valve arranged to automatically open and close, and means for short-circuiting the spark-plug on the pumping cylinder simultaneously with the opening of the valve.

In testimony whereof I have affixed my signature in presence of two witnesses.

CHARLES FRANCIS JENKINS.
